(57) **CLAIM**

The ornamental design for a transparent bag, as shown and described.

DESCRIPTION

FIG. 1 is a front, perspective view of the transparent bag of the present invention in a partially open position with a light unilluminated;

FIG. 2 is a front, elevational view thereof;

FIG. 3 is a rear, elevational view thereof;

FIG. 4 is a side view thereof;

FIG. 5 is an opposite side view thereof;

FIG. 6 is a top view thereof;

FIG. 7 is a bottom view thereof; and,

FIG. 8 is a front, elevational view of the bag of FIG. 1 with the light illuminated.

The broken line showing of handles and a pocket, in FIGS. 1–8, and a tree and fence, in FIGS. 1–3 and 8, are for illustrative purposes only and form no part of the claimed design. In FIGS. 1–7, the light in the pocket is shaded to show it as opaque in contrast to the transparency shading on the bag. The light in FIG. 8 is shaded to show it illuminated yellow.
